UNITED STATES PATENT OFFICE.

HENRY W. EASTHAM, OF BEVERLY, MASSACHUSETTS, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,209,822.

Specification of Letters Patent. Patented Dec. 26, 1916.

Application filed March 6, 1915. Serial No. 12,539.

To all whom it may concern:

Be it known that I, HENRY W. EASTHAM, a citizen of the United States, residing at Beverly, in the county of Essex and State 5 of Massachusetts, have invented certain new and useful Improvements in Buttonhole-Sewing Machines; and I do hereby declare the following to be a full, clear, and exact description of the invention, such as will 10 enable others skilled in the art to which it appertains to make and use the same.

The invention relates to that class of buttonhole sewing machines in which the stitch forming mechanism is rotated during the 15 sewing about the end and eye of the button-hole.

The invention is intended primarily as an improvement in the buttonhole sewing machine shown and described in Patent No. 26 1,063,880, June 3, 1913, although it is not confined in its application to this machine, but may be embodied with advantage in other machines.

In the machine of the above patent the 25 stitch forming mechanism is rotated, rotation after rotation, in the same direction in sewing about successive buttonholes, and in order to prevent the twisting together of the stay and under threads they are led to the 30 turret on which the under thread mechanism is mounted through guides carried by a vertical guide tube which is rotated in unison with the turret and in the opposite direction. The threads lead horizontally from the end 35 of the guide tube to the guides at the lower end of the turret, and it has been found that with certain kinds of thread they may become entwined or twisted to such an extent between the guide tube and turret as to interfere with the proper operation of the 40 machine.

It is the object of the present invention to overcome this difficulty, and to that end the invention contemplates the provision of 45 thread separating guides arranged between the guide tube and turret and mounted to rotate in unison with the turret and tube. The guides are arranged to maintain the threads, and particularly their horizontal 50 runs, in such relation that they cannot contact or twist together in such manner as to interfere with the proper supply of thread to the thread handling devices carried by the 55 turret. The guides may be of any suitable construction and arrangement, and may be

rotated in any suitable manner. It is preferred, however, to form the guides, in whole or in part, of flexible tubes through which the threads may be led, and to rotate the guides by connecting the flexible tubes at 60 one end to the vertical guide tube. It is also preferred to so construct the guides and the supports therefor that they may be readily removed in case the machine is to be used under conditions which render the use of the 65 guide tubes unnecessary or inadvisable.

The invention will be readily understood from an inspection of the accompanying drawings and the following detailed description of the mechanism illustrated therein. 70

In the drawings, Figure 1 is a side elevation, partly in section, showing so much of a buttonhole sewing machine as is necessary to illustrate the application of the present invention thereto. Fig. 2 is a detailed view 75 showing the means for supporting one end of the flexible guide tubes; Fig. 3 is a sectional view on line 3—3, Fig. 2; and Fig. 4 is a detailed view of the coupling for detachably connecting the ends of the guide 80 tubes with the lower end of the vertical guide tube.

In the drawings the invention is shown as embodied in the buttonhole sewing machine shown and described in Patent No. 1,063,880 85 above referred to. In this machine the stitch forming mechanism comprises an upper needle 2, an under needle 4, and a co-operating looper (not shown). The upper needle is eccentrically secured to a reciprocating needle bar 6 which is mounted in a rotary sleeve. The under thread mechanism is mounted in a turret 8 which is rotated in unison with the sleeve carrying the upper needle bar during the sewing, the turret and 90 sleeve being given a single revolution during the sewing of each buttonhole, and being rotated, rotation after rotation, in the same direction in sewing successive buttonholes. The under sewing thread 10 and the stay 100 thread 12 are led to the thread guiding and handling devices on the turret through the hollow link 14 which is carried by the turret, and forms a part of the mechanism through which the under thread mechanism 105 is actuated. The lower end of the link is provided with a sleeve 16 in which the guides 18 and 20 for the sewing thread and stay thread respectively are formed. To avoid the twisting together of the stay and 110

sewing threads by the successive rotations of the turret in the same direction, the threads are supplied through a vertical guide tube 22 which is rotated in a direction opposite to that of the turret, and is given a rotation for each rotation of the turret. This guide tube carries a support 24 for one of the threads, preferably the stay thread, and also carries a guide 26 through which the sewing thread passes. The stay thread is led from the thread supply on the support 24 down through the tube 22, while the sewing thread is led from its supply through the guide 26 which directs the thread from a point in line with the axis of the tube 22 down about the stay thread supply and into the tube 22 below the support 24. The threads pass on opposite sides of a separating pin 28 which divides the lower end 20 of the tube 22 into two thread guides or passages.

In embodying the invention in the machine above described, thread guides are provided intermediate the lower end of the 25 guide tube 22 and lower end of the turret which are arranged to keep the threads separated, and are rotated, rotation after rotation with the guide tube and turret. As shown, the guides for keeping the threads separated comprise two flexible tubes 30 which may be conveniently formed of coiled wire, as indicated in Figs. 3 and 4. These tubes are connected at one end to a coupling head 32 which is provided with bayonet 35 slots 34 by which the head may be readily connected with or disconnected from the pin 28 at the lower end of the guide tube 22. The other ends of the tubes 30 are secured in a head 36 and communicate with holes 38 40 through which the threads lead. The head 36 is provided with an annular groove 40 adapted to be engaged by the supporting bearing plates 42 and 44. The bearing plates are provided with substantially semi-circular recesses within which the head 36 fits, and within which it is free to rotate. The bearing plate 44 is secured to a fixed bracket 46, while the bearing plate 42 is pivoted to the bearing plate 44 at 48, so 45 that it may be readily swung into the dotted line position indicated in Fig. 2 in removing or inserting the guiding tubes. The bearing plate 42 is normally held in position to co-operate with the plate 44 by a spring 50. The support for the head 36 is preferably 50 arranged adjacent to and substantially under the lower end of the turret, so that the threads 10 and 12 will lead directly from the head to the guides 18 and 20 at the lower 55 end of the connecting rod 14. The guide tubes 30 may be twisted together, as indicated in Fig. 1, at the curved portion connecting the horizontal part of the tubes with the lower end of the guide tube 22. The 60 tubes may also be connected at suitable 65

points by solder or otherwise, so that they will be maintained in close relation during their rotation.

While it is preferred to form the rotary guides, in whole or in part, of flexible tubes, 70 and to rotate the guides by connecting the flexible tubes with the end of the guide tube, this is not essential, and it will be understood that the guides may be otherwise constructed and arranged, or otherwise rotated, 75 without departing from the broader features of the invention.

Having explained the nature and object of the invention, and specifically described one form of mechanism in which it may be 80 embodied, what is claimed is:—

1. A buttonhole sewing machine, having, in combination, stitch forming mechanism, a rotary turret in which the mechanism is mounted, two thread guides connected to rotate with the turret, thread supply guides through which the threads lead to the turret guides mounted to rotate about an axis different from that of the turret guides, thread separating guides intermediate the 90 axis of the thread supply guides and the axis of the turret guides, and means for rotating said separating guides rotation for rotation with the turret and thread supply guides. 95

2. A buttonhole sewing machine, having, in combination, stitch forming mechanism, a rotary turret in which the mechanism is mounted, two thread guides connected to rotate with the turret, an oppositely rotating 100 vertical tube having guides for two threads, and rotary thread separating guides through which the threads pass horizontally between the tube and turret.

3. A buttonhole sewing machine, having, 105 in combination, stitch forming mechanism, a rotary turret in which the mechanism is mounted, two thread guides connected to rotate with the turret, a rotary tube provided with guides for two threads, and two flexible 110 guide tubes connected at one end with said tube and at the other end with a rotary head adjacent the turret thread guides.

4. A buttonhole sewing machine, having, in combination, stitch forming mechanism, 115 mechanism for rotating the stitch forming mechanism in the same direction rotation after rotation in sewing about successive buttonholes, guides for the sewing and stay threads rotating with the stitch forming 120 mechanism, thread supply guides through which the sewing and stay threads lead to the guides on the stitch forming mechanism, means for rotating the thread supply guides in a direction opposite to that in which the 125 stitch forming mechanism is rotated, and thread separating guides intermediate the thread supply guides and the guides on the stitch forming mechanism connected to rotate with the thread supply guides. 130

5. A buttonhole sewing machine, having, in combination, stitch forming mechanism including upper and under thread handling devices, a turret in which the under devices are mounted, mechanism for rotating the turret in the same direction rotation after rotation in sewing about successive buttonholes, guiding devices on the turret for the sewing and stay threads, a vertical guide tube provided with guides at its lower end for the under and stay threads, a thread supply support on the tube, means for rotating the tube in a direction opposite to that in which the turret is rotated, and thread separating guides intermediate the tube and turret connected to rotate with the guide tube.
6. A buttonhole sewing machine, having, in combination, stitch forming mechanism, a rotary turret in which the mechanism is mounted, two thread guides connected to rotate with the turret, a rotary tube provided with guides for two threads, two flexible

- 20

guide tubes provided at one end with a coupling head for connecting them to the guide tube, a head in which the other ends of the tubes are secured, and a bearing for said head arranged adjacent the guides on the turret.

7. A buttonhole sewing machine, having, in combination, stitch forming mechanism, a rotary turret in which the mechanism is mounted, two thread guides connected to rotate with the turret, a rotary tube provided with guides for two threads, two flexible guide tubes provided at one end with a coupling head for detachably connecting them with the guide tube, a head in which the other ends of the tubes are secured, and a bearing for the head adjacent the turret comprising fixed and movable sections.
